DESIGN FOR A CENTERING HEAD

William F. Boyce, Houston, Tex.

Application January 29, 1945, Serial No. 117,651

Term of patent 14 years

(Cl. D52—1)

To all whom it may concern:

Be it known that I, William F. Boyce, a citizen of the United States residing at Houston, in the county of Harris, in the State of Texas, have invented a new, original, and ornamental Design for a Centering Head, of which the following is a specification, reference being had to the accompanying drawing, forming a part thereof.

Figure 1 is a front elevational view of the centering head showing my new design.

Figure 2 is a side elevational view, and
Figure 3 is a top plan view thereof.

I claim:

The ornamental design for a centering head,
as shown.

WILLIAM F. BOYCE.
